ADJUSTABLE GUARD ARRANGEMENT FOR SHOE
FINISHING APPARATUS
Roy E. Smith and Robert C. Tyler, Atlanta, Ga., assignors
to The Auto-Soler Company, a corporation of Georgia
Filed Feb. 23, 1965, Ser. No. 434,416
9 Claims. (Cl. 12—92)

This invention relates generally to shoe finishing apparatus and in particular to an improved arrangement for locating work positioning guard elements to exceptional advantage for use in relation to the trimming cutters of such apparatus.

For the finishing steps in shoe repair operations, a rotating cutter is normally provided for the initial trimming of soles, heels, and the like to the proper shape for final finishing; and work positioning or guard members are commonly provided for locating the work at the rotating cutter so that trimming may be accomplished without scarring adjacent portions of the shoe being handled. One guard member is normally located in shrouding relation to the cutter element and is arranged for axial adjustment to cooperate with a relatively fixed edge guard member to vary the exposed width of the cutter element in relation to the width or thickness of the sole or heel piece to be trimmed.

The shrouding guard members have heretofore been adjusted in a number of ways, all of which are generally characterized by an associated mounting permitting the guard member to move axially with respect to the cutter element and by a set screw or other clamping element that must be loosened to allow adjustment and tightened to maintain the guard member at an adjusted position. Such arrangements require the operator first to loosen the set screw manually, then position the guard member by hand and finally retighten the screw, all of which is not only quite unhandy but much less subject to control in providing a proper adjustment than is desirable.

The present invention provides an arrangement by which the shrouding guard member is maintained freely adjustable so as always to be easily set for precisely the extent of exposed cutter width that is needed.

Generally characterized, the present invention comprises a collar member mounted at a fixed position concentrically about the cutter element drive shaft and arranged interiorly for carrying the shrouding guard member so as to maintain it freely adjustable at all times in the axial direction of the drive shaft for selectively setting the exposed width of the cutter element, as described in further detail below in connection with the accompanying drawings, in which:

FIG. 1 is a fragmentary detail in quarter section of an adjustable guard arrangement embodying the present invention;

FIG. 2 is an exploded perspective view of the various elements of the arrangement illustrated in FIG. 1;

FIG. 3 is a further detail corresponding to FIG. 1, but showing the illustrated arrangement adjusted to expose a greater cutter width;

FIG. 4 is a side elevation of a second embodiment of the present invention;

FIG. 5 is a further elevation corresponding generally to FIG. 4, but showing the normally fixed guard member thereof shifted to a retracted position, and being partly broken away and sectioned to show the frictional drag provided for the adjustable guard member; and

FIG. 6 is a further elevation, partly broken away and sectioned, that shows the FIG. 4 structure as seen from the right.

Referring now in detail to the drawings, FIGS. 1 to 3 illustrate a sole trimming embodiment of the present in-

2

vention in which a fixed collar member 10, carried suitably by the frame structure (not shown) of the shoe finishing apparatus involved, has a main bearing 12 fitted therein to support a rotating drive shaft 14 on which a cutter element 16 is clamped between a locating sleeve 18 and a first work positioning guard member 20. The locating sleeve 18 is fitted on the drive shaft 14 so as to rotate therewith at a fixed position, while the first work positioning guard member 20 is secured sidewise of the cutter element 16 by a mounting screw 22 at the end of shaft 14. A second work positioning guard member 24 is carried concentrically on the drive shaft 14 by a mounting arrangement rendering it axially adjustable with respect to the first guard member 20 for determining therebetween the exposed width of the cutter element 16.

The second work positioning guard member 24 includes a fluted head portion 26 presenting finger portions 28 intermeshing with cutter element 16 below the cutting radius thereof and extending beyond the cutting radius 20 with an inclination directed away from the first work positioning guard member 20 to form a smooth front surface portion 30 thereat. A sleeve portion 32 formed integrally with fluted head portion 26 is slidably fitted in a bearing unit 34 and positioned about locating sleeve 18 25 with a slight clearance to permit axial movement of the second work positioning guard member 24 with respect to cutter element 16.

Axial movement of the second work positioning guard member 24 is provided for by arranging bearing unit 34 30 within an axially adjustable shank element 36 that is slidably fitted in collar member 10. The bearing unit 34 is urged against a lock ring 38 fitted in groove 40 in shank element 36 by a relatively heavy compression spring 42 bottomed at main bearing 12, and a relatively light compression spring 44 acts between bearing unit 34 and the fluted head portion 26 for yieldably maintaining abutment at a second lock ring 46 fitted in groove 48 of sleeve portion 32 so that the second work positioning guard member 24 is carried in following relation by shank element 36. The axial urging of heavy compression spring 42 at shank element 36 yieldably maintains the rearward wall 50 of a helical slot 52 formed therein in abutment with a fixed guide element 54 formed at the end of a stud 56 installed in collar member 10 to locate axially the shank element 36 and the second work positioning guard member 24 carried thereby.

In FIG. 1, the second work positioning guard member 24 is illustrated at its closest position with respect to first work positioning guard member 20 with the fluted head portion 26 thereof shrouding substantially the entire cutter element 16 so that no portion thereof is exposed for trimming. To adjust the axial position of the second work positioning guard member 24 to provide a desired exposed cutter element width for trimming soles or the like, the operator grasps shank element 36, which may conveniently be roughened as at 58 for this purpose, and turns it with respect to collar member 10 thereby causing the helical slot wall 50 to slide against fixed guide element 54 which adjusts the axial position of shank element 36 55 and the second work positioning guard member 24 carried thereby. For example, FIG. 3 illustrates the second work positioning guard member 24 at its adjusted position furtherest from first work positioning guard member 20 leaving a maximum width of cutter element 16 exposed 60 for trimming. To provide a plurality of selective settings for second work positioning guard member 24 intermediate the extreme positions illustrated in FIGS. 1 and 3, helical slot wall 50 includes a plurality of notched portions 50' arranged for sequentially engaging the guide element 54 as shank element 36 is turned. At each setting, the exposed cutter element width is slightly less than 65 70

the corresponding thickness of the sole to be trimmed so that as the sole is placed against cutter element 16 the second work positioning guard member 24 is pushed slightly rearwardly against the bias of light compression spring 44 while heavy compression spring 42 maintains shank element 36 at its set position. The inclined front surface portions 30 of the fluted head portion 26 are thereby urged against the sole being trimmed to round off the edge thereof as is usually done by the inclined rear edge 16' of cutter element 16. In addition, the floating action of the second work positioning guard member 24 will accommodate nicely at any setting the small thickness variations normally found in sole material.

In FIGS. 4 to 6, a second embodiment of the present invention is illustrated in a form of the type disclosed and claimed in related copending application Serial No. 387,428, filed August 4, 1964, by Roy E. Smith, and employed for trimming top lifts and the like. A fixed collar member 110, which is normally attached to a frame structure (not shown), has a cylindrical opening 112 through which a shaft 114 extends for driving a cutter element 116 bottomed against a locating sleeve 118 fixed to shaft 114; the cutter element 16 being secured thereto by a screw and washer arrangement 120 threaded into drive shaft 114 (FIG. 6).

Formed integrally with collar member 110 is a fixed mounting post 122 having a clevis member 124 pivotally mounted thereon by a pivot shaft 126. A first work positioning guard member 128 is secured to clevis member 124 for normal disposition sidewise of the cutter element 116 as illustrated in FIGS. 4 and 6, while being selectively shiftable to a second displaced position clearing the cutter element 116 for removal from drive shaft 114 (FIG. 5), all as described in greater detail in the aforementioned copending application Serial No. 387,428.

The cylindrical opening 112 of collar member 110 is threaded at 130 to engage cooperating threads 132 on shank portion 134 of a second work positioning guard member 136 which is thereby maintained freely adjustable at all times in the axial direction to cooperate with the first work positioning guard element 128 for selectively setting the exposed cutter element width.

Opening into cylindrical opening 112 at the threaded surface 130 thereof is a radial bore 138 (FIG. 5) arranged to contain an abutment element 140 which is urged against threads 132 of shank element 134 by a compression spring 142 which also bears against a plug screw 144 threaded into the outer portion of radial bore 138. By turning plug screw 144, the friction drag imposed at threads 132 by abutment element 140 is regulated to maintain the second work positioning guard member 136 at its adjusted position yet freely adjustable to other positions whereby the exposed cutter element width can be selectively set.

With this arrangement of elements, the operator may change the setting of the exposed cutter element width by grasping the second work positioning guard member 136 at a roughened surface portion 146 and turning it for axial adjustment with relation to first work positioning guard member 128. A properly calibrated scale 148 may be provided at the exterior surface of second work positioning guard member 136 in relation to an indicator 150 at the adjacent portion of collar member 110 to enable the operator to set selectively the desired exposed cutter element width quickly and precisely. Also, in this regard, it will be understood that a similar scale and indicator may be provided between collar member 10 and shank element 36 of the sole trimming apparatus illustrated in FIGS. 1 to 3. However, whether or not a scale arrangement of this sort is provided as a guide for adjustment, it should be noted that both of the embodiments described above allow cutting width adjustment to be made readily and safely without stopping the cutter, and additionally make a substantial adjustment in cutting width possible without any necessity for changing cutters,

both of which features are of important advantage in contrast with comparable devices heretofore available.

The present invention has been described in detail above for purposes of illustration only and is not intended to be limited by this description or otherwise except as defined in the appended claims.

We claim:

1. In shoe finishing apparatus of the character described including a rotating cutter element mounted on a drive shaft with a first work positioning guard member disposed sidewise of said cutter element at a normally fixed disposition with respect to the axial direction of said drive shaft and a second work positioning guard member carried exteriorly of and closely adjacent said rotating cutter in concentric shrouding relation with respect to the opposite side thereof for determining the exposed width of said cutter element, the improvement which comprises a collar member mounted at a fixed position concentrically about said drive shaft and threaded interiorly for carrying said second guard member, and an exteriorly threaded shank portion formed integrally with said second guard member fitted in said collar member for maintaining said second guard member freely adjustably at all times in the axial direction of said drive shaft for selectively setting said exposed cutter element width.
2. In shoe finishing apparatus of the character described including a rotating cutter element mounted on a drive shaft with a first work positioning guard member disposed sidewise of said cutter element at a normally fixed disposition with respect to the axial direction of said drive shaft and a second work positioning guard member carried in concentric shrouding relation with respect to the opposite side of said cutter element for determining the exposed width thereof, the improvement which comprises a collar member mounted at a fixed position concentrically about said drive shaft and formed interiorly with means for carrying said second guard member, and a shank element associated with said second guard member and fitted in said collar member and cooperating with said carrying means for engagement thereby to support said second guard member and associated shank element in spaced relation to said drive shaft, the engagement of said shank element by said collar member being adapted to maintain said second guard member freely adjustable at all times in the axial direction of said drive shaft for selectively setting said exposed cutter element width.
3. The improvement for shoe finishing apparatus as defined in claim 2 and further characterized in that said collar member and said shank element having respective engaging surface portions formed to cause said axial adjustment of the second guard member when said shank portion is rotated with respect to said collar member.
4. The improvement for shoe finishing apparatus as defined in claim 2 and further characterized in that said collar member is interiorly threaded and said shank element is exteriorly threaded for providing axial adjustment of said second guard member upon rotation of said shank element, and in that said shank portion is formed integrally with said second guard member for supporting said second guard member in spaced relation to said drive shaft.
5. The improvement for shoe finishing apparatus as defined in claim 4 and further characterized in that said collar member is provided with an abutment element biased into contact with said threaded shank element for providing sufficient friction drag thereat to maintain said second guard element at its adjusted position.
6. The improvement for shoe finishing apparatus as defined in claim 2 and further characterized in that said collar member is formed to present a guide element projecting radially inward thereof, and in that said shank element is formed to include a helically arranged abutment surface portion disposed to bear against said guide

element to cause axial adjustment of said second guard member when said shank element is rotated with respect to said collar member.

7. The improvement for shoe finishing apparatus as defined in claim 6 and further characterized in that said abutment surface includes a series of notched portions formed therein and arranged for sequentially engaging said guide element as said shank portion is rotated in said collar member, and in that biasing means is provided to act axially against said shank element for yieldably maintaining said engagement whereby the adjusted positions of said second guard member provide a plurality of selective sequential settings for said exposed cutter element width.

8. The improvement for shoe finishing apparatus defined in claim 2 and further characterized in that bearing means is provided for rotatably supporting said second guard member in said associated shank element, and in that said second guard member is mounted for limited axial movement with respect to said bearing means and said shank portion and biased axially toward said first guard member whereby said exposed cutter element width is normally maintained at its selected setting by

said axial bias while minor variations in work thickness are accommodated against said bias.

9. The improvement for shoe finishing apparatus as defined in claim 8 and further characterized in that said second guard member is mounted for rotation with said cutter element and includes a fluted head portion presenting finger portions internesting with said cutter element below the cutting radius thereof and extending beyond said radius with an inclination directed away from said first guard member.
